LENS EDGING MACHINE

Eli Maynard Long, Geneva, N. Y., assignor to
 Shuron Optical Company, Inc., Geneva, N. Y., a
 corporation of New York

Application October 2, 1937, Serial No. 167,008

15 Claims. (Cl. 51—101)

This invention relates to improvements in a lens edging machine in which a lens holding means operates in conjunction with a rotating abrasive stone or wheel.

5 An object of the invention is to provide a machine having a rotating abrasive wheel for grinding the edge of a lens, with a simply constructed and controlled lens holder adapted to be oscillated about an axis arranged in a plane extending substantially normal to the axis of rotation of the wheel, whereby the angular position of the lens with respect to the grinding surface of the abrasive wheel will be constantly changing as the lens is moved back and forth across said 10 15 grinding surface from one side thereof to the other.

Another object of the invention is to provide simple control means adapted to be manually operated for altering the path of travel of the 20 lens holder during the oscillation thereof, whereby lenses of various cross-sectional contours or curvatures may be properly positioned with respect to the grinding surface of the abrasive wheel to obtain maximum and uniform travel 25 of all lenses transversely of the abrasive wheel.

A further object of the invention is to provide an improved lens holder for a lens edging machine whereby the lens may be quickly and accurately mounted therein and without the necessity of utilizing a portable lens chucking or centering device which is usual when positioning lenses in lens edging machines as heretofore constructed.

A still further object of the invention resides 35 in providing a grinding machine of the above mentioned class with a lens holder having a limited movement toward and from the abrasive wheel and to provide means for adjusting the abrasive wheel toward the work holder to compensate for wear of the wheel during use.

An additional object of the invention is to provide a lens edging machine with a signaling device so constructed and controlled that the operator may readily determine from a position at 45 a distance from the machine, when the grinding of the edge of each lens is completed.

A still further object of the invention is to provide a lens edging machine with an improved truing device for the abrasive wheel.

50 Other objects and advantages pertaining to the construction of the device and to the form and relation of parts thereof will more readily appear from the following description taken in connection with the accompanying drawings, in 55 which:

Figure 1 is a top plan view of a lens edging machine embodying the various features of this invention.

Figure 2 is an enlarged vertical sectional view taken substantially in the plane of the line 2—2, 5 Figure 1, and illustrating a portion of a water receptacle associated therewith and portions of the stone or abrasive wheel and base broken away.

Figure 3 is a horizontal sectional view taken substantially in the plane of the line 3—3, Figure 10 2.

Figure 4 is an enlarged detail vertical sectional view through the upper portion of the machine and taken substantially on line 4—4, Figure 1.

Figure 5 is a detailed horizontal sectional view 15 taken on line 5—5, Figure 2.

Figure 6 is a detail sectional view taken on line 6—6, Figure 5.

Figure 7 is a detail vertical sectional view taken on line 1—1, Figure 5.

Figure 8 is a perspective view of a lens clamp suitable for securing a lens to one of the clamping heads of the lens holder illustrated in Figures 1, 2 and 5.

Figures 9 and 10 are detail vertical sectional 25 views taken respectively on lines 9—9 and 10—10, Figure 5.

Figures 11, 12 and 13 are detail sectional views taken respectively on lines 11—11, 12—12 and 13—13, Figure 10.

Figure 14 is an enlarged detail sectional view taken substantially on line 14—14, Figure 4.

Figure 15 is a detail vertical sectional view taken substantially in the plane of the line 15—15, Figure 1.

Figure 16 is a diagrammatic view illustrating the action of the lens during the oscillation thereof across the grinding surface of the abrasive wheel.

As illustrated in the drawings, the machine 40 comprises a supporting base or frame 1 composed of two sections, a lower section 2 and an upper section 3, which are fixedly secured together by any suitable means as screws 4. The abrasive wheel 5 is firmly clamped to opposed collars 6 and 7 which are fixedly secured to a shaft 8 to rotate therewith. The shaft 8 extends at its ends beyond the adjacent collars 6 and 7 and is journaled in suitable bearings 9 connected with a cradle or rock frame 10 which is provided with a central opening 11 for receiving the wheel 5 therein. This frame or cradle 10 is a substantially rectangular member adapted to be readily received within the chamber 2' of the lower base section 2, while the bearing members 9 are se- 45 50 55

cured to said frame or cradle intermediate the ends thereof so that the shaft 8 extends transversely of the frame in a substantially horizontal plane.

5 The rear end of the cradle 10 is pivotally connected by a horizontally disposed shaft 12 to the upper section 3 of the base 1 in a plane above and at the rear of the center of the base 1, as shown in Figures 2 and 3. The cradle 10 is adapted to 10 extend forwardly and downwardly from the shaft 12 to a position within the lower section 2 of the base 1 adjacent the forward end thereof. Rotatably mounted in the forward end of the cradle 10 is a pin 13 which is arranged in substantially 15 parallel relation with the shaft 12 and has one end thereof extending outwardly beyond the adjacent side of the frame or cradle 10, as shown in Figure 3.

An adjusting screw or bolt 14 is mounted in 20 screw-threaded engagement with the outer end of the pin 13 and extends upwardly therefrom through a suitable opening provided in an offset portion 3' of the upper base section 3, as shown in Figures 1 and 2. This bolt 14 is utilized for adjusting the forward end of the frame or cradle 10 and thereby elevate the wheel 5, as the same 25 wears away in use, for maintaining the peripheral surface of the wheel in cooperative relation with a lens holder 16 mounted on the upper section 3 of the main supporting base or frame 1 in a plane 30 above the wheel 5.

The lens holder, in this instance, comprises opposed, coaxial clamping heads 17 and 17' mounted end to end upon coaxial rotary shafts or 35 spindles 18 and 18' which, in turn, are journaled in suitable bearings 19 and 19' provided in the outer or free portion of a vertical swinging frame or carriage 20 pivoted at 21 to the forward portion of a horizontally swinging frame 22. The 40 frame 22 has the rear portion thereof pivotally connected by a pair of axially spaced pivotal members or hinge pins 23 and 23' to the rear portion of the upper section 3 of the base 1, the axes of the pivotal pins 23 and 23' being arranged in a plane extending substantially normal to the axis 45 of rotation of the wheel 5 and spindles 18 and 18'.

The adjacent ends of the lens clamping heads 17 and 17' are provided with the usual pads 25 composed of rubber, leather or the like for frictionally engaging the opposite faces of the lens to cause the latter to rotate with the collars and also to reduce the liability of breakage of the lenses or marring the lenses when clamping them between the heads. The heads 17 and 17' may be of any 50 desired shape or outer configuration, depending upon the shape of the lens to be ground, and are preferably removably connected with their respective spindles. One of the heads, as 17, has the face thereof adjacent the head 17' provided with diametrically disposed guide lines 26 and 26', cut or stamped thereon, arranged to extend across the head in right angular relation to each other for assisting in correctly positioning the lens thereon in a manner which will hereinafter be 55 more fully explained.

The bearing members 19 for the shaft or spindle 18 are mounted in axially spaced relation in a bearing supporting member or head 28 which, in this instance, is T-shaped in cross section, as 60 shown in Figure 5, with the bearings mounted at opposite ends of the transverse portion 28' thereof. The laterally extending portion 29 of the bearing support is a tubular member which is rotatably mounted in a suitable opening extending 65 inwardly from the forward side of the carriage 20

adjacent one end thereof. This bearing support 28 is maintained in operative relation with the carriage 20, by a screw member 30 which extends through an elongated slot 31 formed in the carriage 20 and is screw-threaded into the adjacent portion of the member 29, as shown in Figures 5 and 7. The axis of the bearing support portion 29 is arranged at substantially right angles to the axis of the spindle 18 so that by rotating the bearing member 28 about the axis of the portion 29 thereof, the head 17, connected with the spindle 18, may be moved from the position in coaxial alignment with the head 17' to a position at one side thereof, as indicated by broken lines in Figure 7. The length of the slot 31 is such that this 10 rotary movement of the bearing support 28 is substantially equal to 90°, whereby the head 17 may be moved from a horizontal position in cooperative relation with the head 17' to a vertical position 15 above the member 28, with the clamping 20 surface of the head containing the guide lines 26 and 26' uppermost in position to be readily seen by the operator.

The bearing support 28 is releasably locked in either of said horizontal or vertical positions by 25 a spring actuated lock pin 32, which is slidably mounted in the carriage 20 for axial movement into and out of engagement with either one of a pair of apertures 33 formed in the bearing portion 29 of the bearing support 28 in right angular 30 relation with each other, as indicated in Figure 7. The lock pin 32 extends from the bearing member 29 toward the opposite end of the carriage 20 in substantially parallel relation with the spindles 18 and 18' and has the end thereof adjacent the 35 spindle 18' provided with a diametrically disposed slot 32' which receive therein the free end of an arm 35. The arm 35 is secured at the other end to a vertically disposed shaft or stud 36 rotatably mounted in the carriage 20 intermediate the pin 40 32 and spindle 18'.

A second arm 37 is secured to the stud 36 to extend outwardly therefrom in substantially right angular relation to the arm 35 and has the free 45 end thereof adapted to be engaged by a pin 38 secured to an enlarged, cylindrical portion 39 of a control shaft 40, which is journaled in the carriage 20 at one side of and in parallel relation to the stud 36. The pin 38 is mounted in eccentric 50 relation with the control shaft 40 so that, as said shaft is rotated in one direction, the pin 38 will produce a corresponding rotation of the arm 37, stud 36 and arm 35 for moving the lock pin 32 out of one of the apertures 33.

As shown in Figure 7, the enlarged portion 39 of the control shaft 40 is journaled in the upper portion of the carriage 20, while the lower portion 41 of the shaft is of considerably less diameter than the portion 39 and is journaled in the lower portion of the carriage 20 in coaxial relation with the portion 39. The rotation of the control shaft 40 in one direction is limited by a pair of stop pins 43 and 43', one of which is secured to the shaft portion 39 adjacent the outer face of the carriage 20, as shown in Figure 7, 65 while the other pin is secured to the carriage 20 as indicated in Figure 1. The arrangement of the pins 43 and 43' is such that the pins 38 will be prevented from moving in one direction beyond the arm 35 out of engagement therewith. 70

The control shaft 40 is provided with an eccentric portion 44 arranged intermediate the portions 39 and 41 and which extends through a vertically disposed recess 45 formed in a control arm 46, which is secured to a pin 47 rotatably con- 75

5 nected with the carriage 20 at the rear of the control shaft 40. The arm 46 extends forwardly from the pin 47 and has the forward end thereof bifurcated and operably connected to the spindle 18' by a grooved collar 48 fixedly secured to said spindle, so that as the arm is rocked about the axis of the stud 47 by the eccentric 44, the spindle 18' will be moved axially in one direction or the other for bringing the head 17' connected therewith into and out of cooperative relation with the head 17 for releasably clamping a lens between said heads.

10 The relation of the pin 38, arm 35, eccentric 44 and arm 46 is such that when the control shaft 15 40 is moved in a direction for separating the heads 17 and 17', the pin 38 will not engage the arm 35 until the head 17' has approached nearly the limit of its outward movement so that the lock pin 32 will remain in holding engagement 20 with the bearing support 28 upon the normal movement of the head 17' into and out of holding engagement with a lens positioned between head 17' and the head 17. It, therefore, follows that a lens clamped between the heads 17 and 17' 25 may be released therefrom during normal axial movement of the spindle 18', and when it is desired to release the bearing support 28, this may be accomplished by a slight additional rotary movement of the control shaft 40 in a direction 30 to produce further outward movement of the spindle 18', whereupon the pin 32 will be moved axially out of holding engagement with the bearing portion 29 by the engagement of the pin 38 with the arm 35. This rotation of the control 35 shaft 40 for actuating the lock pin 32, which is in an anti-clockwise direction in this instance, is limited by the stop pins 43 and 43' as the lock pin is disengaged from the member 29. The rotation of the control shaft 40 may be readily 40 accomplished by means of a hand wheel 50 secured to the upper end of the shaft.

45 In order that the spindle 18 and the head 17 carried thereby may be accurately aligned with the spindle 18' and head 17' when in the horizontal position, I have provided a stop screw 51 which is screw-threaded in the carriage 20 in alignment with the upper end portion of the slot 31 to engage the outer end or head portion of the screw 30 as said screw approaches the 50 limit of its upward swinging movement, as illustrated in Figure 7.

55 The spindles 18 and 18' are rotated in unison and, for this purpose, each of these spindles is operatively connected with a shaft 55, common thereto, in the following manner:

60 The shaft 55 extends longitudinally through the carriage 20 adjacent the rear portion thereof with the end portions of the shaft rotatably supported in corresponding end portions of the carriage. That is, the left-hand end portion of the shaft 55 is journaled in a bearing member 56 mounted in the carriage 20, while the opposite or right-hand portion of the shaft is rotatably mounted in an elongated hub 57 provided on a 65 gear 58, said hub being rotatably mounted in the carriage 20, as shown in Figure 5. The shaft 55 is operatively connected with the spindle 18 by means of a pair of spiral gears 59 and 60, one of which is secured to the shaft 55 and the other 70 gear 60 is secured to a short shaft 61 which is journaled in a bearing member 62 mounted in the portion 29 of the bearing support 28 in coaxial relation therewith. The forward end of the shaft 61 has secured thereto a bevel gear 63 75 which is in meshing engagement with a bevel

gear 64 secured to the spindle 18 adjacent the inner bearing member 19.

80 The shaft 55 is connected with the spindle 18' by means of an idle gear 66 rotatably connected with the carriage 2 in meshing engagement with the gear 58. This idle gear 66 is also in meshing engagement with a spur gear 67 secured to the spindle 18' adjacent the outer end of the collar 48. The face of the gear 67 is of considerably greater width than that of the idle gear 66 so as to remain in constant meshing relation with the idle gear during the axial movement of the spindle 18' for bringing the head 17' into and out of cooperative relation with the head 17 and also during the operation of the lock pin 32 to bring the same out of holding engagement with the bearing support 28.

85 The shaft 55, in this instance, is rotated from the abrasive wheel shaft 8 and, for this purpose, the shaft 8 is provided with a worm 70 secured to one end thereof which is extended beyond the adjacent bearing member 9, as shown in Figures 3 and 4. The worm 70 is in meshing engagement with a worm gear 71 mounted on a stub shaft 72 which is journaled in a gear housing 73 connected with the adjacent side of the frame or cradle 10. The shaft 72 extends in substantially right angular relation to the shaft 8 and has secured thereto a worm 74 which meshes with a worm gear 75 secured to the lower end of a shaft 76 also journaled in the gear housing 73. This shaft 76 extends outwardly beyond the upper wall of the housing 73 and has the upper end thereof provided with an enlarged tubular portion 77 which, in turn, is provided with a pair of 90 diametrically disposed slots 78 extending inwardly from the upper or outer end thereof. Connected with the tubular portion 77 of shaft 76 to be driven by said shaft is an extension shaft 79 having a head 81 connected to the lower end thereof and which is slidably mounted within the tubular member 77. To the head 81 is secured a pin 82 which extends outwardly at both ends beyond the adjacent portion of the head into the slots 78, as shown in Figure 4. The other end of the shaft 79 is connected by a suitable universal joint structure 83 with a stub shaft 84 journaled in the lower portion of the carriage 20 beneath the shaft 55. To the upper end of the shaft 84 is secured a bevel gear 85 which is in meshing engagement with a corresponding gear 86 rotatably mounted upon the shaft 55 adjacent the gear 58 (see Figure 5).

95 The gear 86 is releasably connected with the shaft 55 by a clutch mechanism which, in this instance, comprises a finger knob 88 slidably mounted upon the outer end of the shaft 55 which extends beyond the adjacent portion of the carriage for receiving said knob. The knob 88 is secured to the shaft 55, to rotate therewith, 100 by means of a screw 89 connected with the knob and which projects into an elongated recess 90 provided in the peripheral surface of the shaft 55.

105 Secured to the inner end portion of the finger knob 88 is a plurality of clutch pins 91 arranged in circumferential spaced relation to each other about the shaft 55. These pins 91, two of which are shown in Figure 5, extend inwardly from the knob 88 through corresponding apertures formed 110 in the hub portion 57 of the gear 58 and are adapted to move into and out of corresponding apertures provided in the gear 86. It is thus apparent that when the finger knob is in its innermost position, the clutch pins 91 will operatively 115

connect the gear 86 to the gear 58 and knob 88 for transmitting motion to said gear 58 and knob 88 and thence to the shaft 55 through the screw 89.

It will now be observed that when the knob 88 is in its innermost position, rotation of the shaft 8 will produce a corresponding rotation of the shaft 55 and, when the knob 88 is in its outermost position, as determined by the coaction of the screw 89 and recess 90, shaft 55 will be disconnected from operative relation with the shaft 8 and may be manually rotated by manipulation of the knob 88, whereby the spindles 18 and 18' may be manually rotated when necessary.

The shaft 8 and abrasive wheel 5 may be rotated from any suitable source of power through the medium of a belt, not shown, and a pulley 93 secured to the collar 7 as illustrated in Figure 3.

In order that the spindles 18 and 18' will operate smoothly and with a maximum amount of efficiency when a lens is clamped between the heads 17 and 17', one of the spindles, as 18, may, as shown in Figures 5 and 9, have secured thereto a brake drum or collar 95 positioned between the gear 64 and the outer bearing member 19. This drum 95 is engaged by a spring pressed plunger 96 slidably mounted in a tubular case 97 secured to the supporting member 28 to extend outwardly therefrom substantially radially from the axis of the spindle 18. A screw 98 may, as shown, be screw-threaded in the outer end of the case 97, whereby the pressure of the pin 96 upon the drum 95 may be controlled. The frictional engagement of pin 96 with drum 95 produces sufficient drag upon spindles 18 and 18' that backlash occurring in the gear members connecting said spindles with the shaft 55 and also the drive mechanism connecting shaft 55 with shaft 8 will not produce vibration of said spindles.

As illustrated more clearly in Figures 5 and 15, the pivotal pins 21 for connecting the carriage 20 with the frame 22 are arranged a short distance below the shaft 55 and provide the carriage 20 with a limited swinging movement sufficient to operably maintain the lens carried by the heads 17 and 17' in grinding engagement with the peripheral surface of the abrasive wheel or stone 5. In order that the swinging movement of the housing 20 may be manually controlled, I have provided the housing with a suitable lever 100 connected with the rear portion adjacent the left-hand end thereof, as shown in Figures 1 and 15.

The lever 100 is provided with a laterally disposed arm or extension 101 which projects rearwardly and downwardly therefrom, as shown in Figure 15, and has pivotally connected thereto, as at 102, a latch member 103. This latch member extends rearwardly some distance from the pivot 102 and has the rear portion thereof provided with an elongated slot 104 which slidably receives therein a pin 105 secured to the frame 22. The length of the slot 104, of course, determines the amount of swinging movement of the carriage 20 about pins 21, and the upper end of the slot is provided with a laterally disposed portion 104' adapted to receive pin 105 therein. The outer lower side of slot portion 104' provides a shoulder 106 adapted to engage the pin 105 for releasably maintaining the carriage in the uppermost position.

The latch member 103 extends forwardly a short distance beyond the pivot 102 into close proximity to the upper end of the lever 100 and

forms a fingerpiece 103' whereby the operator, when grasping the lever 100, may readily effect the upward movement of the rear end portion of the latch member to bring the pin 105 out of engagement with the shoulder 106 and into the major portion of the slot 104, and thus release the carriage and permit the same to rock downwardly about the pivots 21 to bring the lens carried by the heads 17 and 17' into pressure engagement with the peripheral surface of the wheel 5.

The pressure engagement of the lens with the wheel 5 may be readily controlled, in this instance, by a weight 108 which is slidably mounted upon a bar 109 secured to the outer ends of side portions 110 of a U-shaped bracket 111 which is positioned exteriorly of the base 1 adjacent the left-hand side thereof. Bracket 111 is securely fastened intermediate its ends to one end of a stub shaft 112 which is journaled in said side of the base section a short distance in front of the shaft 8. The shaft 112 extends into the interior of the case section 2 and has secured to the inner end thereof one end of an arm 113 which extends rearwardly from the shaft beneath the adjacent bearing member 9 and has the outer end thereof connected with the outer end of the arm 101 by a link 114.

The weight 108 is clamped to the bar 109 by means of a thumb screw 115 so that the weight 108 may be adjusted along said bar from a position at one side of the shaft 112 to a position at the other side thereof to produce a corresponding increase or decrease in the pressure of the lens with the wheel 5.

As hereinbefore stated, the lens carried by the clamping heads 17 and 17' is moved transversely of the grinding or abrasive wheel 5, back and forth across the peripheral surface of said wheel during the grinding operation. This movement of the lens is produced by oscillation of the frame 22 about pivotal pins 23 and 23'. In order that this oscillatory movement of the frame 22 may be produced by power means, I have provided the shaft 76 with an eccentric cam 117 (see Figures 4 and 14) arranged thereon adjacent the upper face of the gear housing 73 between said housing and the tubular member 77.

A pitman 118 is journaled at one end upon the eccentric cam 117 and extends rearwardly therefrom and has the other end thereof pivotally connected by means of a spring-pressed plunger 119 and a take-up screw 120 mounted in the rear end of the pitman to a control shaft 121 journaled in the frame 22 at one side of the axis of rotation thereof. As shown in Figures 1 and 4, shaft 121 has the lower end thereof reduced in diameter and provided with a spherical portion 121' which is arranged in eccentric relation with the shaft and is clamped between the screw 120 and plunger 119, said screw and plunger being provided with concave recesses in their adjacent ends for receiving the spherical portion 121' therein.

In order to positively maintain the pitman in engagement with the lower end of the control shaft 121, I have provided an adjustable rest, in the form of a screw 122, mounted in a lateral projection 123, formed on the frame 22 beneath the shaft 121, said screw 122 being arranged substantially coaxially with the shaft 121. The upper end of the screw 122 slidably contacts the pitman 118 so that the pitman may readily move relative thereto during the rotation of the shaft 121.

In grinding lenses of different curvatures, it often becomes necessary to shift the path of movement of the heads 17 and 17' with respect to the wheel 5 to maintain the lens in proper relation with the wheel. This shifting of the frame, as will be readily apparent, is obtained by rotating the shaft 121 to swing the frame 22 in one direction or the other about the pivotal pins 23 and 23' and with respect to the pitman 118, whereby the center of oscillation of the clamping heads will be in the plane or at one side of the center line of the peripheral surface of the abrasive wheel to maintain the center of oscillation of that portion of the lens edge contacting the wheel substantially midway between the sides of said wheel.

The rotation of control shaft 121 is manually performed by means of a rod 125 secured to the upper end of the shaft 121. This rod 125 has the outer end thereof secured to a cylindrical head 126 which extends transversely of the rod so as to lie in the plane passing through the spherical portion 121' and through the axis of the shaft 121. The end of the head 126 positioned at the same side of the rod 125 as the spherical portion 121' is preferably tapered, as at 126', so as to indicate to the operator the position of the spherical portion 121' with respect to the shaft 121, whereby the operator may readily determine in which direction to rotate shaft 121 when it becomes necessary to adjust the position of frame 22 and carriage 20 for grinding a lens of predetermined form.

The throw of the eccentric cam 117 and the spacing of the control shaft 121 with respect to the axis of oscillation of the frame 22 is such that as the shaft 126 is rotated the lens carried by the heads 17 and 17' will be moved from in close proximity to one side surface of the wheel 5 to the other side surface thereof and the stroke of oscillation of the frame and, therefore, of the carriage 20, will remain uniform for all positions of member 121'. In other words, rotation of the spherical member 121' about the axis of control shaft 121 will produce a corresponding movement of member 121 toward or from the axis of rotation of cam 117. This results in a corresponding increase or decrease in the effective length of pitman 118. When the member 121' is adjusted to produce a maximum effective length of pitman 118, as shown in Figure 14, the center of oscillation of clamping heads 17 and 17' will be at the right-hand side of the center line of the peripheral surface of wheel 5 when viewed from the front. When the effective length of pitman 118 is reduced to a minimum by member 121' being moved to that side of the axis of control shaft 121 remote from cam 117, the center of oscillation of heads 17 and 17' will be at the left-hand side of the center line of the peripheral surface of wheel 5. In either of the positions of member 121' the edge of a concavo-convex lens may be ground and when the edge of a substantially flat lens is to be ground, member 121' is adjusted to produce an intermediate effective length of pitman 118.

In order that the edge of a lens may be accurately ground to produce a lens of circular or predetermined, non-circular shape, the spindle 18 is extended a short distance outwardly beyond the outer bearing member 19 and the adjacent side of the bearing support 28, and has secured thereto a collar 128. This collar is provided with a pair of diametrically disposed dowel pins 129 which project laterally from the outer face thereof to

extend into corresponding openings provided in a former or pattern 130 for supporting said former or pattern. The former 130 is releasably secured to the collar 128 by a pair of spring jaws 131 mounted in the outer end portion of the spindle 18 and which extend outwardly from said spindle through a central opening provided in the former 130, as shown in Figure 5.

Beneath the former 130 is mounted a back-rest 133 which is in the form of an arm pivotally connected, as at 134, Figure 10, to a bracket 135 secured by screws 136 to an adjustable support 137 which, in this instance, is in the form of a rod slidably mounted in a suitable recess 138 provided in an extension 139 secured to or made integral with the frame 22.

The support 137 extends above the extension 139 and has the upper end portion thereof provided with screw threads which are engaged by a graduated index wheel 140. This wheel 140, when in contact with the upper surface of the extension 139 has the upper surface thereof aligned with a projection or lug 142 formed integral with the adjacent portion of the frame 22, as shown in Figure 5. This projection 142 is provided with an index mark or line 143 adapted to register with successive graduating lines 144 formed on the upper surface of the wheel 140 in uniform circumferential spaced relation with each other. The spacing of the graduating lines 144 is so related to the pitch of the screw-threads formed on the upper end of the support 137 that when the wheel is rotated a distance equal to the spacing of two adjacent lines 144, the bracket 135 will be raised or lowered with respect to the frame 22 a distance equal to the difference in length of the major diameter of a corresponding lens and that of the lens of the next size.

The back-rest 133 has the upper surface thereof of slightly curved outwardly and is provided with a shoe or hardened contact plate 145 adapted to be engaged by the peripheral edge of the former 130 during the grinding of the lens. This back-rest 133 is provided with a stud 146 (see Figure 13) which extends outwardly from one side thereof in a plane over the upper edge of the bracket 135 in slightly spaced relation thereto. A screw 147 passes through the stud 146 and is screw-threaded into the adjacent portion of the bracket 135.

Surrounding the screw 147 and positioned between the stud 146 and bracket 135 is a spring 148 which yieldingly urges the stud 146 outwardly into engagement with the head of the screw which limits the outward movement of the stud and back-rest 133. The inner movement of the back rest and stud 146 is limited by the engagement of the stud with the adjacent edge of the bracket 135. Secured to the end of the back rest 133, opposite the pivot 134, is a pin 149 which extends downwardly therefrom and has the lower end thereof provided with a tip 150 composed of rubber or other suitable insulating material for operating an electric switch 151 connected to the bracket 135.

The switch 151 comprises a supporting block 152 composed of fibre or other suitable insulating material and which is secured, in any suitable manner, to the bracket 135, as shown in Figure 10. Secured to the block 152 is a spring 70 contact element 153 which extends beneath the tip 150 in slightly spaced relation to a second contact element 154 also secured to the block 152, said contact element 153 being adapted to be moved downwardly into engagement with the 75

contact 154 when the back rest is moved downwardly against the action of the spring 148. The engagement of the contact 153 with contact 154 closes an electric circuit C connected with said contacts for the purpose of operating a signal S which, as diagrammatically illustrated in Figure 10, is in the form of an incandescent lamp.

In order that water may be supplied to the abrasive wheel 5 for moistening the same, I have provided a receptacle 156 mounted upon a bracket 157 secured to the frame 22, as indicated in Figure 2. The receptacle is shown provided with a control valve 158 associated with an outlet opening 159 provided in the bottom of the receptacle. A delivery tube 160, in communication with outlet opening 159, extends forwardly therefrom to a position over the wheel 5 a short distance at the rear of the clamping heads 17 and 17'.

When operating, the abrasive wheel 5 is rotated in an anti-clockwise direction, as viewed in Figure 2. In order that the dust formed in grinding and excess water carried on the peripheral surface of the stone will not be carried over the top of the stone, I have provided the upper base section 3 with a tubular case 161 in the rear portion thereof and which is arranged in the plane of the wheel 5 intermediate the bearing members 23 and 23', and extends outwardly from the base section through an opening 162 formed in the frame 22. In the case 161 is slidably mounted a tubular holder 163 which is adapted to extend through the case 161 to within a short distance of the peripheral surface of the wheel 5 and has mounted in the inner end portion thereof a sponge 164 adapted to bear against the peripheral surface of the wheel 5. The inner diameter of the holder 163 is substantially equal to or slightly greater than the width of the stone 5 so that the sponge 164 will not only collect abrasive material carried by said stone, but will also function to spread the water carried thereby across the peripheral surface of the stone.

In order that the abrasive wheel 5 may be maintained in the most efficient grinding condition, I have provided a novel truing device which is operatively connected with the base 1 to be used as occasion may require. This truing device, as shown more clearly in Figure 2, comprises a substantially rectangular hone or carbide stick 165 which is adjustably clamped by a plate 166 and screws 167 to the head 168 of a support 169. This support 169 includes a cylindrical extension 170 which is connected with the head 168 and extends outwardly therefrom through a sleeve 171 which is screw-threaded in a suitable aperture 172 formed in the front wall of the upper base section 3.

The inner end of the sleeve 171 engages a shoulder 173 provided on the support 169 at the junction of the portion 170 with the head 168. The extension 170 projects a short distance outwardly from the sleeve 171 and has a lever 174 secured thereto, whereby the holder 168 may be rotated about the axis of the extension 170. This handle 174 engages the outer end of the sleeve 171 and coacts with the shoulder 173 for preventing relative axial movement of the support 169 and sleeve 171. The support 169 is adjusted axially toward and from the wheel 5 by the axial movement of the sleeve 171 as the same is screw-threaded into and out of the opening 172.

In order that the sleeve 171 may thus be readily turned to effect the axial adjustment thereof, I have provided the outer end portion of said sleeve with a hand wheel 175. The sleeve 171

is secured in the adjusted position by a screw 176 mounted in the base section 3. The position of the sleeve 171 in the base section 3 is such that the hone 165 will extend in substantially radial relation to the abrasive wheel 5 with the inner end of said hone normally arranged in parallel relation with the adjacent portion of the peripheral surface of the abrasive wheel. The width of the hone 165 is substantially equal to the width of the wheel 5. The distance the hone 165 is arranged at one side of the axis of rotation of the head 168 preferably exceeds one-half the width of the abrasive wheel so that the hone will swing back and forth across the face of the stone in an arc having its center lying in the axis of the extension 170. It will, therefore, be seen that instead of the inner end of the hone having a concave recess ground therein during the truing of the wheel 5, said end of the hone will be maintained substantially flat with the result that the hone will have a line contact with the peripheral surface of the wheel 5 during the truing operation. The hone will, therefore, true the abrasive wheel surface much more rapidly and accurately than when the hone is operated, in the conventional manner, that is, toward and from the surface of the abrasive wheel in a straight line substantially normal to said surface, whereby the inner end of the hone engages the surface of the wheel throughout substantially its entire area. The head 168 may, as shown, be provided with a recess 168' extending inwardly from the end thereof adjacent the wheel 5 for the reception of a sponge 178 adapted to normally bear against the peripheral surface of the wheel for preventing water and dust collecting on the hone 165.

The operation of the device will now be understood to be substantially as follows:

The wheel 5 is maintained with the upper peripheral surface thereof in cooperative relation with the clamping heads 17 and 17' by manipulation of the bolt 14 to produce upward swinging movement of the cradle 10 as the peripheral surface of the wheel is worn away. After the correct former or pattern 130 for the lens to be ground has been selected, the back-rest 133 is adjusted relative to the frame 22 by the manipulation of the index wheel 140 to bring the graduation mark 144, corresponding to said former or pattern, into registration with the index line 143 on the frame 22.

The bolt 14 is next manipulated to bring that portion of the peripheral surface of the wheel 5 adjacent the back-rest 133 into the transverse plane of substantially the central portion of the outer face of the shoe 144, so that when the former or pattern engages the shoe, a corresponding portion of the lens will be in contact with the peripheral surface of the wheel 5 and the center of the lens, which is positioned in alignment with the center of the former 130, will be spaced from the adjacent surface of the wheel 5 a distance corresponding to the spacing of the center of the former from the outer surface of the shoe 144. It, therefore, follows that the lens mounted between the clamping heads 17 and 17' will be ground so as to conform in outer configuration to that of the former or pattern 130.

If it is desired that the edge of the lens be ground so that the finished lens will be slightly larger or slightly smaller than the former used, the back-rest may be readily adjusted to accomplish this by turning the index wheel 140 to

bring the index line thereon corresponding to the former a little to one side of the index line 143.

In mounting the lens between the heads 17 and 17' in proper alignment therewith, the first step comprises releasing the bearing support 28 by manipulating the hand wheel 50 in a direction to effect withdrawal of the lock pin 32 from engagement with the bearing portion 29 in the manner hereinbefore described. As the bearing supporting member 28 is thus released, the operator rotates said member by utilizing the case member 97 as a handle to swing the spindle 18 from the horizontal position to a vertical position with the head 17 arranged above the bearing support 28, as indicated by broken lines in Figure 7. This moving the head 17 to the upright position will bring the guide lines 26 and 26' into position to be readily viewed by the operator. As the spindle 18 is brought to the vertical position, the member 28 will be locked against further rotary movement by the engagement of the pin 32 in the aperture 33 in registration therewith as the operator releases the hand wheel 50.

The operator may now position the lens to be ground upon the head 17 and accurately center the lens with the head by utilizing the guide lines 26 and 26' in conjunction with the dots or other markings which are previously placed in the usual manner on the lens denoting the optical centers and the major and minor axes of the lens. After the lens has thus been properly placed upon the head 17 in engagement with the pad 25, the lens is secured to the head by any suitable means, such as the clamp A illustrated in Figure 8, by bringing one of the jaws, as a, into engagement with the lower face of the head 17, and the other jaw, as b, into contact with the upper face of the lens L, as indicated in Figure 7.

After the lens has thus been placed on and secured to the head 17 by clamp A, the accuracy of the relation of the lens to the head 17 may be readily determined by utilizing a sight opening 180 and the lens further adjusted, if necessary, relative to the head 17. Sight opening 180 is provided in the outer end of a bar or rod 181 secured to the carriage 20 in a plane over the axis of rotation of the member 28 and which has the sight opening 180 thereof arranged in alignment with the axis of the spindle 18 when said spindle is in the vertical position. After the lens L has thus been properly mounted upon the head 17, the member 28 is again released by the manipulation of the hand wheel 50 and then rotated to bring the spindle 18 to the horizontal position with the lens secured to the head 17 by the clamp A. As the spindle arrives at the horizontal position, the member 28 is locked against further rotary movement by the pin 32 as the operator rotates the hand wheel 50 in a direction to cause the spindle 18' to move inwardly toward the spindle 18 for bringing the head 17' into engagement with the lens for clamping said lens between said head 17' and the head 17. After the lens has been securely clamped by the heads 17 and 17', the clamp A is removed from the lens.

It will be observed, by referring to Figure 8, that the jaw member b is provided with a relatively large recess b' which is of sufficient size to readily receive the head 17' therein when the clamp is in engagement with the lens carried by the head 17. The machine is now ready to operate for grind-

ing the edge of the lens and, for this purpose, the wheel 5 may be rotated by any suitable source of power operatively connected with the pulley 93.

As the abrasive wheel 5 is thus rotated, the carriage 20 is released by the operator moving the latch member 103 to bring the pin 105 out of engagement with stop shoulder 106 and into alignment with the major portion of the slot 104. As the carriage 20 is thus released, it will swing downwardly about the pins 21 as an axis and bring the edge of the lens clamped between the heads 17 and 17' into contact with the peripheral surface of the abrasive wheel 5 to effect grinding thereof. As the wheel is thus rotated, the frame 22 will be oscillated about the axis 0 common to both pivotal members 23 and 23' due to the action of the eccentric cam 117 upon the frame 22 through the medium of the pitman 118. During the oscillation of the frame 22 and the carriage 20 connected therewith, the lens clamped between the heads 17 and 17' will be moved across the peripheral surface of the wheel 5 from adjacent one side thereof to the other side. During this movement of the lens across the face of the wheel 5, the lens will be swung from a position at the center of the peripheral surface of the wheel in substantially parallel relation with the wheel, as indicated by full lines in Figure 16, into more or less angular relation with the peripheral surface of the wheel as the lens approaches the outer edges thereof, as indicated by broken lines in Figure 16. It will, therefore, be seen that the lens is not only moved transversely across the peripheral surface of the abrasive wheel from one side thereof to the other, but its angular relation with respect to the grinding surface of the wheel is also constantly changing. This not only provides a maximum amount of travel of the lens for a minimum width of wheel, but also provides for a maximum speed in the grinding operation.

Furthermore, it will be noted that the signal S will not only indicate to the operator when the grinding of the edge is completed, but will also indicate to a certain degree the progress in the grinding operation being made. This latter result is due to the unground lens being more or less irregular in outline so that portions of the lens edge will become ground before other portions and the signal S will be operated, intermittently prior to the completion of the grinding operation. To explain more explicitly the lens to be ground is usually cut prior to the edge grinding operation somewhat larger in size than that desired for the finished lens. Each of these pre-cut lenses after having been mounted in the lens holder is moved downwardly into operative position. The lens carried by the holder is held in contact with the abrasive wheel by the co-action of the adjustable weight 108 and the lens holder 16. This contact of the lens with the wheel maintains the pattern 130 out of contact with the back-rest 133 during the initial grinding of the lens. However, as hereinbefore stated certain portions of the edge of the lens will become ground to the proper amount before other portions thereof, at which time the pattern will engage the back-rest and prevent further grinding of the finished portions of the lens. This intermittent engagement of the pattern with the back-rest will of course cause intermittent operation of the signal S and the length of time between successive operations of the signal will gradually decrease as the lens approaches the finished state by the more frequent engagement of the pattern.

or former with the back-rest 133 until said back-rest is continuously maintained depressed by the former and the signal S remains in continuous operation thus indicating that the grinding operation is completed.

5 Although I have shown and particularly described and preferred embodiment of my invention, I do not wish to be limited to the exact construction shown, as various changes, both in the 10 form and relation of the parts thereof, may readily be made without departing from the spirit of the invention as set forth in the appended claims.

I claim:

15 1. In a machine for grinding the edge of a lens, an abrasive wheel having a substantially flat peripheral surface and rotatable about a predetermined axis, a support for a lens holder movable about an axis in a plane extending substantially normal to said axis of rotation of the 20 abrasive wheel, lens holder elements connected with said support to rotate about an axis substantially parallel with said axis of rotation of the wheel for supporting a lens edgewise against the 25 peripheral surface of the wheel, the axis of movement of the support being substantially parallel with the radial line of the abrasive wheel passing through the point of contact of the lens with said wheel, and power means for rotating said wheel and lens holder and for oscillating said support.

20 2. A machine for grinding the edge of a lens as in claim 1, having manually operable means for shifting said support about the axis of movement thereof independently of the oscillatory movement produced by the power means.

25 3. In a machine for grinding the edge of a lens, an abrasive wheel having a substantially flat peripheral surface and rotatable about a predetermined axis, a support for a lens holder including a frame movable about an axis in a plane extending substantially normal to said axis of rotation of the abrasive wheel, a carriage, rotatable lens holder elements connected with said carriage, means pivotally connecting the carriage with said frame whereby the carriage may swing about an axis substantially parallel with the axis of rotation of the abrasive wheel to move the lens holder elements toward and from the wheel, the axis of movement of the frame being substantially parallel with the radial line of the abrasive wheel 30 passing through the point of contact of the lens with said wheel, and power means for rotating said wheel and lens holder elements and for oscillating said frame.

35 4. In a grinding machine of the class described having a support and an abrasive wheel mounted on said support to rotate about a horizontal axis, a frame, a carriage, a pair of spindles journaled in said carriage in coaxial relation with each other, clamping elements connected with said spindles normally spaced apart to receive the lens between them, means pivotally connecting the carriage with the frame whereby said carriage may swing about a horizontal axis to move the 40 clamping elements toward and from the abrasive wheel, means pivotally connecting the frame to the support so constructed and arranged that the plane of swinging movement of the frame is substantially normal to the radial line of the abrasive wheel passing through the point of contact of the lens with said wheel and power means for rotating said wheel and spindles and for oscillating said frame.

45 5. In a grinding machine of the class described 50 having an abrasive wheel, a rotary lens holder

5 for supporting a lens edgewise against the peripheral surface of the wheel, said lens holder including a pair of coaxial lens engaging means normally spaced apart for receiving the lens between them, and means rotatably supporting one of said lens engaging means whereby the same may be swung out of coaxial alignment with the second one of said lens engaging means so that a lens may be accurately positioned on said one of the lens engaging means.

10 6. In a lens edging machine having a rotary abrasive wheel, in combination, a lens holder for supporting a lens edgewise against the peripheral surface of the wheel comprising two opposed clamping heads arranged to receive the lens between them, means including a pair of spindles for rotating said heads, and supporting means for one of said spindles mounted to rotate about an axis extending substantially normal to the axis of rotation of the spindle whereby the head 15 connected with said spindle may be swung into and out of cooperative relation with the other head.

15 7. In a lens edging machine as in claim 6, manually operable means connected with the second one of said spindles for producing axial movement thereof to bring the head carried thereby toward and from the other clamping head for releasably clamping a lens between them.

20 8. In a lens edging machine as in claim 6, manually operable means connected with the second one of said spindles for producing axial movement thereof to bring the head carried thereby toward and from the other clamping head for releasably clamping a lens between them, and means actuated by said manually operable means including a locking element engageable with the supporting means for releasably maintaining said supporting means in either of 25 two rotary positions.

25 9. In a lens edging machine having a rotary abrasive wheel, in combination, a lens holder for supporting a lens edgewise against the peripheral surface of the wheel comprising a pair of spindles, opposed clamping heads connected to said spindles to receive the lens between them, supporting means for said spindles including an element rotatably supporting one of the spindles and having movement with respect to the other spindle whereby the head connected with said one spindle may be moved into and out of axial alignment with the other spindle and head, and means for rotating said spindles in unison.

30 10. In a lens edging machine having a rotary abrasive wheel provided with a substantially flat peripheral surface, a base, a support for said wheel mounted on said base for movement with respect to said base, a rotary lens holder, a support for said lens holder operatively connected with the base and including relatively swinging members mounted for movement with respect to said base to move the lens holder toward and from the abrasive wheel and to swing the lens holder across said surface of the abrasive wheel in a 35 plane substantially normal to the radial line of the wheel passing through the point of contact of a lens carried by the lens holder with said wheel, means connected with said wheel support for moving the abrasive wheel toward the lens 40 holder, and separate means connected with one of said supports for maintaining the lens carried by the lens holder in predetermined pressure engagement with the abrasive wheel.

35 11. In a lens edge grinding machine, a base, a 45

5 rotary abrasive wheel having a substantially flat peripheral surface and supported by said base, a frame pivotally connected to the base to swing in a plane extending substantially parallel with the axis of rotation of the abrasive wheel, a rotary lens holder, a carriage supporting said lens holder pivotally connected with the frame to swing the lens into and out of engagement with the peripheral surface of the abrasive wheel, a 10 former operatively connected with the lens holder to rotate therewith and to swing in unison with said carriage, a back-rest for the former connected with the frame to swing therewith, said plane of swinging movement of the frame being substantially normal to the radial line of the abrasive wheel passing through the point of contact of the lens with said wheel for normally maintaining the lens in contact with said wheel surface throughout the arc of movement of the lens independently of 15 relative swinging movement of the carriage and frame, and power means for rotating the abrasive wheel and lens holder and for oscillating said frame.

12. A grinding machine as in claim 11, having 20 means for adjusting the back-rest with respect to said frame.

13. In a grinding machine of the character described having an abrasive wheel, a lens holder for supporting a lens edgewise against the peripheral surface of the wheel, said lens holder including a pair of rotatable lens engaging means normally arranged in coaxial relation with each other and adapted to be spaced apart for receiving the lens between them, rotatable means supporting one of said lens engaging means so that the same may be swung to an inoperative position out of coaxial relation with the second of said lens engaging means whereby a lens may be readily placed thereon, and means having a hole 30 therethrough arranged in fixed predetermined relation with said one of the lens engaging means when in said inoperative position providing a sight opening by which the lens may be accurately positioned thereon.

14. In a grinding machine of the character described having an abrasive wheel, a rocking lens holder for supporting a lens edgewise against the peripheral surface of the wheel, said lens holder including a pair of rotatable lens engaging means 5 normally arranged in coaxial relation with each other and adapted to be spaced apart for receiving a lens between them, supporting means for one of said lens engaging means having an axis of rotation substantially normal to the axis of rotation of said one of the lens engaging means so that said latter means may be swung to an inoperative position out of coaxial relation with the second of said lens engaging means whereby a lens may be readily placed thereon, and means 15 having a hole therethrough arranged substantially coaxial with said one of the lens engaging means when the same is in the inoperative position providing a sight opening by which the lens may be accurately positioned on said latter 20 means.

15. In a lens edge grinding machine, an abrasive wheel, a supporting means therefor, a carriage, means pivotally connecting the carriage to the supporting means whereby the carriage 25 may have a limited swinging movement toward and from the abrasive wheel, a lens holder comprising a pair of spindles rotatably supported by said carriage, a former mounted on one of said spindles, a back rest connected with the supporting means to be engaged by the former during the grinding of the lens edge, said back rest having a limited movement with respect to the supporting means when engaged by the former, and 30 electrically operated signal means including contact elements connected with the back rest and the support in electrical spaced relation to each other, said contact elements being normally spaced from each other and adapted to be moved into electrical contact with each other by said 35 limited movement of the back rest.

ELI MAYNARD LONG.
